Filed Jan. 26, 1970, Ser. No. 21,089

Term of patent 7 years

Int. Cl. D12—99

U.S. Cl. D48—32

FIG. 1 is a front elevational view of a motor vehicle lamp lens showing my new design, the faceted lens surface being fragmentarily shown in the center area for convenience of illustration, it being understood that the faceting appears throughout said area;

FIG. 2 is a view taken along line 2—2 of FIG. 1;

FIG. 3 is a view taken along line 3—3 of FIG. 1; and

FIG. 4 is a view taken along line 4—4 of FIG. 1.

I claim:

The ornamental design for a motor vehicle lamp lens, substantially as shown and described.
